UNITED STATES PATENT OFFICE.

EDWARD M. SEARS, OF AKRON, OHIO, ASSIGNOR TO THE B. F. GOODRICH COMPANY, OF NEW YORK, N. Y., A CORPORATION OF NEW YORK.

DESIGN FOR A PNEUMATIC TIRE.

Application filed March 14, 1924. Serial No. 8,931. Term of patent 14 years.

To all whom it may concern:

Be it known that I, EDWARD M. SEARS, a citizen of the United States, residing at Akron, in the county of Summit and State of Ohio, have invented a new, original, and ornamental Design for a Pneumatic Tire, of which the following is a specification, reference being had to the accompanying drawing, forming a part thereof.

Fig. 1 is a perspective view of a pneumatic tire showing my design.

I claim:

The ornamental design for a pneumatic tire as shown.

EDWARD M. SEARS.
